US0D1057027S

(12) **United States Design Patent** (10) **Patent No.:** **US D1,057,027 S**
(45) **Date of Patent:** **** Jan. 7, 2025**

(54) **GAMING MACHINE**

(71) Applicant: **AGS LLC**, Las Vegas, NV (US)

(72) Inventors: **Rachel Calhoun Lewis**, Atlanta, GA (US); **Karl Frederick Zedell, Jr.**, Alpharetta, GA (US); **Mark Robert Brandau**, Johns Creek, GA (US); **Kevin Lee Hohman**, North Las Vegas, NV (US); **Sigmund Hyunjai Lee**, Atlanta, GA (US); **Ariel David Turgel**, San Francisco, CA (US); **Daniel Kendall Harden**, Palo Alto, CA (US); **Zachary Grey Stephanchick**, San Jose, CA (US)

(73) Assignee: **AGS LLC**, Las Vegas, NV (US)

(**) Term: **15 Years**

(21) Appl. No.: **29/867,039**

(22) Filed: **Oct. 6, 2022**

Related U.S. Application Data

(62) Division of application No. 29/688,849, filed on Apr. 24, 2019, now Pat. No. Des. 969,926.

(57) **CLAIM**

The ornamental design for a gaming machine as shown and described.

DESCRIPTION

FIG. 1 is a front isometric view of a gaming machine.

FIG. 2 is a front elevation view thereof.

FIG. 3 is a rear elevation view thereof.

FIG. 4 is a first side view thereof.

FIG. 5 is a second side view thereof.

FIG. 6 is a top plan view thereof; and,

FIG. 7 is a bottom view thereof.

The shade lines in the Figures show contour and not surface ornamentation. The broken lines in the Figures show portions of the support structure and its surrounding environment that form no part of the claimed design.

1 Claim, 7 Drawing Sheets
